United States Patent Office

Des. 215,466
Patented Sept. 30, 1969

215,466

CLOCK

Howland B. Jones, Jr., Harwich Port, Mass., assignor to
Time & Tide, Inc., Boca Raton, Fla., a corporation of
Florida

Filed Oct. 22, 1968, Ser. No. 14,117

Term of patent 14 years

Int. Cl. D10—01

U.S. Cl D42—7

Fig. 2

Fig. 1

FIG. 1 is a view in front elevation of a clock embodying my new design;

FIG. 2 is a left side elevational view.

The rear is essentially planar and unornamented.

I claim:

The ornamental design for a clock, as shown and described.
